UNITED STATES PATENT OFFICE.

MERCER ERWIN, OF TALMO, GEORGIA, ASSIGNOR OF ONE-HALF TO R. N. MAJOR, OF GAINESVILLE, GEORGIA.

RAIL-JOINT.

1,300,146.

Specification of Letters Patent.

Patented Apr. 8, 1919.

Application filed July 25, 1917, Serial No. 182,753. Renewed January 9, 1919, Serial No. 270,445.

To all whom it may concern:

Be it known that I, MERCER ERWIN, a citizen of the United States, residing at Talmo, in the county of Jackson, State of Georgia, have invented a new and useful Rail-Joint; and I do hereby declare the following to be a full, clear, and exact description of the invention, such as will enable others skilled in the art to which it appertains to make and use the same.

The present invention relates to certain new and useful improvements in rail joints, and has for its object to provide a device of this character which embodies novel features of construction whereby the abutting ends of a pair of rails can be held securely in alignment with each other without the necessity of employing any bolts or threaded fastening members.

Further objects of the invention are to provide a rail joint which is comparatively simple and inexpensive in its construction, which can be used in connection with standard rail sections without necessitating any changes therein, which can be installed without difficulty or loss of time, and which holds the rail ends securely against both vertical and lateral displacement.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawings, in which:

Figure 1 is a side elevation of a rail joint embodying the invention.

Fig. 2 is a top plan view of the same.

Fig. 3 is a transverse sectional view through the joint on the line 3—3 of Fig. 2.

Fig. 4 is a perspective view of the chair member, showing the same as detached from the rail ends.

Corresponding and like parts are referred to in the following description and indicated in all the views of the drawings by the same reference characters.

Specifically describing the present embodiment of the invention, the numerals 1 designate the abutting ends of a pair of rails which may be of any standard or conventional cross section, and the numerals 2 a

series of ties which extend transversely under the track rails in the usual manner. The joint member is in the form of a chair, including a base plate 3 and a pair of opposed integral wings 4 which spring from the edge 60 portions of the base plate and extend over the basal flanges of the rail ends at 4^a, terminating in the vertically disposed plates 4^b which extend into the fishing spaces of the rails and fit tightly against opposite sides of 65 the webs of the rails, also engaging the lower sides of the rail heads so as to hold the rails against relative vertical movement. The vertical plate 4^b of one of the wings 4 is provided upon the inner face thereof with 70 a longitudinally extending groove 5 through which a wire or similar conducting member can be passed. The ends of the base plate 3 are provided with longitudinally projecting integral extensions 6 which extend an appreciable distance under the rails so as to provide an extended bearing for the same. These longitudinal extensions 6 of the base plate are somewhat narrower than the body portion of the base plate, and are provided 80 at opposite sides thereof with hooked lugs 7 arranged to extend over the base flanges of the rails and to assist in holding the rail ends securely in position. The longitudinal edges of the base plate extensions 6 are beveled at 85 8 and provided with the spike receiving notches 9. In a somewhat similar manner the edges of the body portion 3 of the base plate are provided with side flanges 3^a which are notched at 10, the two sets of notches 9 and 10 being engaged by spikes 11 which are employed to secure the device rigidly in position upon the ties 2. The bottom of the chair is entirely flat and the flanges 3^a project outwardly beyond the edges of the extensions 6 so as to form in effect a cross shaped base for the chair. This construction provides a firm bearing for the chair upon the ties, and greatly reduces the possibility of the chair overturning. The abutting ends of the rails 1 are inserted in the chair member, being engaged by the side wings 4 thereof, and also by the hooked lugs 7 of the base plate extensions. The wings 4 confine the rail ends in such a manner that 105 they are held securely against both vertical and horizontal displacement relative to each other, thereby enabling the rolling stock to pass over the joint without excessive jarring or jolting.

Having thus described the invention, what I claim as new and desire to secure by Letters Patent, is:—

A combination with the abutting ends of a pair of rails, of a chair member including a base plate having flat upper and lower faces and provided at an intermediate point in its length with opposed side wings constructed to fit over the flanges of the rails and extend upwardly within the fishing spaces to engagement with the rail heads, the ends of the base plate being formed with longitudinally projecting extensions which have the edges thereof beveled and notched to receive spikes

and are also provided with short upwardly projecting inwardly hooked lugs for extending over and locking the flanges of the rail ends to the extensions at a distance from the side wings, the upper and lower surfaces of the longitudinal extensions being flush 15 with the top and bottom of the base plate.

In testimony whereof I have signed my name to this specification in the presence of two subscribing witnesses.

MERCER ERWIN.

Witnesses:

A. S. ERWIN,

W. D. (BILL) WHELCHEL.
